UNITED STATES PATENT OFFICE.

ALEXANDER McMARTIN STARK, OF TORONTO, CANADA.

COMBINED TELEPHONE, TELEGRAPH, ELECTRIC-LIGHT, AND POWER SYSTEM.

SPECIFICATION forming part of Letters Patent No. 716,302, dated December 16, 1902.

Application filed July 12, 1901. Serial No. 68,119. (No model.)

To all whom it may concern:

Be it known that I, ALEXANDER McMARTIN STARK, of the city of Toronto and the county of York and Province of Ontario, Canada, have invented a Combined Communicating, Electric-Light, and Power System; and I hereby declare that the following is a full, clear, and exact description of the same.

The object of this invention is to furnish a subscriber with electric light, power, and communication over the same circuit at the same time. In carrying out this object I use a power-current transmitted over a main power-circuit and distributed at each subscriber's station to the subscriber's main circuit to continuously furnish him with current for his lamps, motors, and communication instruments and maintain this power-current at constant tension by storage battery bridged across the main power-circuit between the generator and subscribers' stations.

The drawing represents a diagrammatic view of a complete system of distribution.

Like characters of reference refer to like parts throughout the specification and drawing.

a represents the generator-station, which may contain any number of switchboards, and *bb* the subscribers' stations. Connecting the generator-station with the subscriber's station is a three-wire circuit consisting of two main conductor-wires *d d'* and a main return-wire *e*. Tapping the main conductor-wire *d* and leading to the subscriber's station *b* is the subscriber's conductor-wire *f* in circuit by means of the subscriber's return-wire *h* with the main return-wire *e*. Connected in parallel with the subscriber's conductor and return wires *f* are a series of lamps *g* and a motor *g'*. The electric current continuously circuits over the main conductor-wire *d* to the subscriber's conductor-wire *f*, through the lamps *g*, subscriber's return-wire *h*, to the main return-wire *e*. Tapping the subscriber's conductor-wire *f* is the telephone conductor-wire *i*, leading to the telephone-receiver *j*, in circuit with the telephone-transmitter *k*, which is connected with the subscriber's return-wire *h* by the telephone return-wire *o*, and interposed in the circuit between the tap *l* and receiver *j* is a resistance *m*. The telephone-hook *r'* is

connected to the line-wire *s*, leading to the tip *t* of the plug *u*, and connected to the line-wire *s* is the conductor-wire *a'* of the signal-lamp relay *c'*. The subscriber's signaling device *w* is tapped on the subscriber's return-wire *h* by the wire *w''*, and when the receiver is on the hook *r'* the circuit for the current is established over the line-wire *s* from the central station through the hook *r'*, contact-point *q*, subscriber's signaling device *w*, and wire *w''* to the main return-wire *e*. Connected with the condenser conductor-wire *p* are the wires *x* and *x''*, forming the telegraph-circuit, in which is interposed the usual telegraph instruments *y*. Interposed on the condenser conductor-wire *p*, between the telegraph circuit-wires *x* and *x''*, is a condenser *r*, the purpose of which is to prevent the interrupted current of the telegraph instrument being transmitted to the receiver of the telephone instrument. When the receiver has been removed from the telephone-hook *r'*, the circuit from the central station is from the tip *t* of the plug *u*, line-wire *s*, telephone-hook *r'*, contact-point *q*, condenser conductor-wire *p*, telephone conductor-wire *i*, receiver *j*, and transmitter *k* to the telephone return-wire *o* and main return-wire *e*, and also over the telegraph-circuit, the telegraphic messages being received and transmitted over the telephone-circuit when the telephone-hook is in this position. A similar system of circuits is installed in the subscriber's station *b'*.

Bridged on the main power-circuit is a storage battery *z* to aid in maintaining constant pressure of the current as it circuits from the generator to the subscribers' stations and to remove the effects of the imperfect commutation of the generator and destroy the individual vibrations of the current by a neutralization of the same.

When a subscriber desires to call the central station, the receiver is removed from the hook *r'*, which then engages the contact-point *q* and completes the circuit for the current from the tap *l*, through the resistance *m* and condenser and telegraph circuits to the line-wire *s*, relay-conductor *a'*, and relay *c'*, which it energizes as it passes to the relay return-wire *e'*, tapped on the return line-wire *f'*, connected to the main return-wire *e*, the return

line-wire f' being also connected with the jacket of the plug u .

- In the central station is a secondary battery g' , the conductor-wire h' of which is connected to an armature i' , adapted to be attracted by the relay c' when energized. Opposed to the armature i' is the contact-point j' of the signal-lamp v . The return-wire k' of the secondary battery g' terminates in a contact-point l' , and normally engaging the contact-point l' is the armature m' of the signal-lamp v . The return-wire k' of the secondary battery g' is connected with the return line-wire f' .
- 15 Tapped on the return line-wire f' is the return-wire o' of the secondary relay p' , the magnet of which is opposed to the armature m' . When the current circuits from line-wire s and relay-conductor a' through the relay c' to relay return-wire e' , return line-wire f' , and main return-wire e , the armature i' is attracted to the contact-point j' of the lamp v . The armature m' of the lamp being normally in engagement with the contact-point l' of the battery return-wire k' , it necessarily follows that when the armature i' is attracted to the contact-point j' the secondary battery g' is short-circuited through and lights the signal-lamp to signal the operator that the subscriber has called. The secondary relay p' is in circuit with the spring s' of the jack t' by means of a conductor u' , and when the tip t of the plug u is inserted in the jack t' it engages the spring s' and establishes a circuit for the current from the line-wire s over the spring s' , conductor-wire u' to the secondary relay p' , causing the secondary relay to attract the armature m' and break the circuit of the current of the secondary battery through the signal-lamp v , the circuit of the current through the relay p' being completed by means of the secondary relay return-wire o' to the return line-wire f' and main return-wire e . When the tip t of the plug u is inserted in the jack t' of the second subscriber's station, it engages the line-spring v' in circuit with the line-wire s and establishes a circuit of the current to the signaling device w , which it continues to operate until the receiver is removed from the telephone-hook r' , when the circuit through the signaling device is broken and established through the condenser-circuit to the telephone instruments, telephone return-wire o , and main return-wire e , the circuit of the current being simultaneously established over the telegraph-circuit bridged on the condenser-circuit p .

60 The disconnect-lamp w' is in circuit with the line return-wire f' and is fitted with a spring x' , having an insulated tip z' normally resting against the plug u . When the plug is pulled from its socket and inserted in the jack, the spring x' moves against the contact-point a^3 in circuit with the line-wire s , the circuit of the current thus being established by means of the line-wire s , contact-point a^3 , and spring x' , through the disconnect-lamp

w' . When the circuit of the current has been broken at the subscriber's station, the lamp w is extinguished, and the operator is signaled that the calling-subscriber's instrument is no longer in use.

70 In circuit with the conductor-wire h' of the secondary battery g' is a secondary battery conductor-wire a'' , fitted with a contact-point b'' , adapted when actuated to engage a contact-point c'' of the branch wire d'' of the line-wire s . In circuit with the return-wire k' of the secondary battery g' is a secondary battery return-wire e'' , which is also in circuit 80 with the receiver f'' of the operator's instrument. The operator's instrument is furnished with two wires g'' and h'' , respectively, in circuit with the secondary battery return-wire e'' and fitted with contact-points i'' and j'' , respectively. The contact-point i'' is opposed to the contact-point of a branch wire k'' in circuit with the line-wire s , while the contact-point j'' is opposed to the contact-point of the branch wire l'' in circuit with 90 the return line-wire f'' . The contact-points i'' , j'' , b'' , and c'' are shown in their normal position in the drawing and are brought into engagement with the contact-points of the wires k'' and l'' by the ordinary operating- 95 lever used in telephone-exchanges. The current from generator c is transmitted over the conductor-wires d d' to the subscribers' stations b b' . At the subscribers' stations the current continuously passes over the subscriber's conductor-wire f , through the electric lamps g and motor g^3 , to the return-wire h and main return-wire e . The current through the lamps and motor is not interrupted to any noticeable or appreciable extent by the cutting in of the telephone or telegraph instruments, as hereinafter described, or, in other words, the circuit of the current from the generator through the lamps and motors is continuous and of a sufficiently 105 high potential to perform the work required of it. At the tap l sufficient current is taken off the power-circuit to operate the telephone and telegraph instruments and passes through a resistance m to protect the telephone and 110 telegraph instruments against its high potential. The current circuits continuously from the resistance m through the telephone conductor-wire i , receiver j , transmitter k , telephone return-wire o , to the main return-wire 115 e . In the case of the telephone the circuit of the current is constant through the instruments, while in the case of the telegraph instrument the circuit of the current is interrupted until the telephone-hook r' engages 120 the contact-point q .

Assuming that subscriber's station b desires to communicate with subscriber's station b' , the receiver is removed from the telephone-hook r' , when a circuit from the generator a 130 is established over the subscriber's conductor-wire f , resistance m , condenser and telegraph circuits to the contact-point q , hook r' , and line-wire s to the signal-lamp v . The oper-

ator at the central station after the lighting of the signal-lamp, as above described, brings the contact-points $i'' j''$ into engagement with the contact-points of the branch wires $k'' l''$, 5 respectively, forming a circuit from the line-wire s through the operator's instrument at the central station and line return-wire f' to the main return-wire e , putting the operator's instrument into communication with the instrument at subscriber's station b . The generator-current from subscriber's station terminates in the tip t of the plug u , and the operator on being requested to connect subscriber's station b with subscriber's station b' 10 inserts the tip t of the subscriber's plug u into the jack t' of the subscriber's station b' . For the purpose of more clearly explaining this description it is deemed advisable to designate the plug and jacks of subscribers' stations b by the numerals 1^a and 2, respectively, and the plug and jacks of subscriber's station b' by the numerals 3 and 4, respectively. The plug 1^a is inserted in the jack 4, and the circuit of the current is then from the generator a , through the tip t of the plug 1^a, over the line-spring, line-wire telephone-hook, through the signaling device, signal return-wire, telephone return-wire of subscriber's station b' to the main return-wire e . On the 15 removal of the receiver from the telephone-hook at subscriber's station b' the circuit of the current through the signaling device is broken and is established over the condenser conductor-wire and through the condenser to the telephone instrument and also over the telegraphic circuit and then over the telephone return-wire to the main return-wire e . The subscriber at station b is now in communication with the subscriber at station b' , the 20 generator a continuing to furnish the current for the operation of the instruments, as well as for the operation of the lamps and motors at both stations. When the plug 1^a is inserted in the jack 4, the calling-subscriber's spring x' moves against the contact-point a^3 and establishes a circuit from the generator a over the line-wire s , through the disconnect-lamp w' to the line return-wire f' , the spring x' and contact-point a^3 forming part 25 of the plug-switch. When the generator-circuit from subscriber's station b is broken by the receiver being hung on the telephone-hook r' at subscriber's station b , the circuit through the disconnect-lamp w' is broken and the operator is signaled that the instruments are no longer in use, and the plug 1^a is then disconnected from the jack 4 and returned to its socket. In the case of the subscriber 30 at station b' desiring to speak to the subscriber at station b the same *modus operandi* is put into force, the plug 3 being inserted by the operator into the jack 2. When the operator desires to call the subscriber, the contact-point b'' is brought into engagement 35 with the contact-point c'' and the battery-current from the secondary battery-circuits, through the battery-wire a'' , branch wire d'' , line-wire s , hook r' , signaling device w , wire w'' , to the telephone return-wire o and main return-wire e , operating the signaling device 70 until the subscriber responds by removing the receiver from the telephone-hook r' , when the circuit of the secondary battery is broken through the signaling device and a circuit from the generator a is established by means 75 of the hook r' , line-wire s , relay c' , and line return-wire f' to the main return-wire e , energizing the relay c' to attract the armature i'' to the contact-point j'' , causing the secondary battery to short-circuit through the lamp v 80 and signal the operator that the subscriber has responded. When the circuit of the current is established through the signal-lamp v , the operator knows that the subscriber has responded and brings the contact-points i'' 85 and j'' into engagement with the contact-points of the branch wires k'' and l'' , establishing the speaking-circuit between the operators' and subscribers' instruments over the line-wire s and line return-wire f' , respectively. When the contact-points i'' and j'' have been brought into engagement with the contact-points of the branch wires k'' and l'' , the current circuits from the generator a over the line-wire s , through the wires k'' 90 g'' , instrument f'' , wires $h'' l'$ to the line return-wire f' and main return-wire e . When the instruments are no longer in use, the circuit is broken by the contact-points i'' and j'' being disconnected from the contact-points 95 of the wires k'' and l'' . The operation of the lever which brings the contact-points i'' and j'' into engagement with the contact-points of the branch wire k'' and l'' separates the contact-points b'' and c'' and interrupts the 100 normal circuit of the current from the secondary battery g' to the line-wire s .
 As shown in the drawing, there are three sets of jacks for each of the subscribers' stations b b' , representing three switchboards, 105 being numbered 5, 6, and 7, respectively. It will be noticed that the line-spring v' of each of the jacks is connected with the line-wire s and that the sockets q'' of the jacks are connected by means of wires h^3 . The spring x' 110 is connected with the wires h^3 by means of the wire i^3 . When the plug u is removed from its socket, the current circuits by means of the spring x' , wires i^3 and h^3 to the sockets q'' of the jacks of the subscriber's station b on 115 the various switchboards and terminates in the sockets of the jacks. By this means the sockets of all of the jacks of the subscribers' stations are furnished with battery-current. When the contact-points i'' and j'' are brought 120 into engagement with the branch wires k'' and l'' , a circuit is established between the telephone operator's receiver and the socket of the subscriber's jack through the tip t of the plug. By placing the tip of the plug 125 against the socket q'' of the jack the operator can ascertain whether the line is in use or not. If the current above described is in the socket of the jacks, it will produce a metallic 130

click in the receiver each time the tip of the plug touches the socket of the jack. The contact-springs s' of the jacks t are all in circuit with the conductor-wire u' in order that the insertion of the tip t of the plug u in any one of the jacks will establish the current through the secondary relay p .

Having thus fully described my invention, what I claim as new, and desire to secure by Letters Patent, is—

1. An electric system for the transmission of power and for communication, consisting of a high-voltage circuit, a low-voltage circuit tapped on the high-voltage circuit, and a storage battery interposed on the high-voltage circuit between the source of current and low-voltage circuit, substantially as specified.
2. An electric system for the transmission of power and for communication, consisting of a high-voltage circuit, a series of lamps or motors operated by the high-voltage circuit, a low-voltage circuit tapped on the high-voltage circuit and a storage battery interposed on the high-voltage circuit between the source of power and low-voltage circuit, substantially as specified.
3. An electric system for the transmission of power and for communication, consisting of a high-voltage circuit, a series of lamps or motors in circuit with the high-voltage circuit, a low-voltage circuit tapped on the high-voltage circuit, telephone instruments in circuit with the low-voltage circuit and a storage battery interposed on the high-voltage circuit between the source of power and low-voltage circuit, substantially as specified.
4. An electric system for the transmission of power and for communication, consisting of a high-voltage circuit, a series of lamps or motors in circuit with the high-voltage circuit, a low-voltage circuit tapped on the high-voltage circuit, telegraph instruments in circuit with the low-voltage circuit and a storage battery interposed on the high-voltage circuit between the source of power and low-voltage circuit, substantially as specified.
5. An electric system for the transmission of power and for communication, consisting of a high-voltage circuit, a series of lamps or motors in circuit with the high-voltage circuit, a low-voltage circuit tapped on the high-voltage circuit, telegraph and telephone instruments in circuit with the low-voltage circuit and a storage battery interposed on the high-voltage circuit between the source of power and low-voltage circuit, substantially as specified.
6. An electric system for the transmission of power and for communication, the combination of an electric-light or power circuit, a telephone-circuit tapped on the electric-light or power circuit and a choking means interposed on the light and power circuit between the source of power and the telephone-circuit, substantially as specified.
7. In an electric system for the transmission of power and for communication, the

combination of an electric-light or power circuit, a telegraph-circuit tapped on the electric-light or power circuit and a choking means interposed on the light and power circuit between the source of power and the telegraph-circuit, substantially as specified.

8. In an electric system for the transmission of power and for communication, the combination of an electric-light or power circuit, a telephone-circuit tapped on the electric-light or power circuit, a telegraph-circuit tapped on the telephone-circuit, and a choking means interposed on the light and power circuit between the source of power and the telephone-circuit, substantially as specified.

9. In an electric system for the transmission of power and for communication, the combination of an electric-light or power circuit, a telephone-circuit tapped on the electric-light or power circuit and a storage battery interposed on the electric-light or power circuit between the source of power and the telephone-circuit, substantially as specified.

10. In an electric system for the transmission of power and for communication, the combination of an electric-light or power circuit, a telegraph-circuit tapped on the electric-light or power circuit and a storage battery interposed on the electric-light circuit between the source of power and telegraph-circuit, substantially as specified.

11. In an electric system for the transmission of power and for communication, the combination of an electric-light or power circuit, a telephone-circuit tapped on the electric-light or power circuit, a telegraph-circuit tapped on the telephone-circuit and a storage battery interposed on the electric-light circuit between the source of power and telephone-circuit, substantially as specified.

12. An electric system for the transmission of power and for communication, consisting of a main high-voltage circuit, a subscriber's high-voltage circuit tapped on the main high-voltage circuit, electric lamps or motors operated by the subscriber's high-voltage circuit, a low-voltage circuit tapped on the subscriber's high-voltage circuit, telephone instruments operated by the low-voltage circuit and a storage battery interposed on the high-voltage circuit between the low-voltage circuit and source of power, substantially as specified.

13. An electric system for the transmission of power and for communication, consisting of a main high-voltage circuit, a subscriber's high-voltage circuit tapped on the main high-voltage circuit, a low-voltage circuit tapped on the subscriber's high-voltage circuit between the low-voltage circuit and main high-voltage circuit, substantially as specified.

14. An electric system for the transmission of power and for communication, consisting of a main high-voltage circuit, a subscriber's high-voltage circuit tapped on the main high-voltage circuit, a series of lamps or motors in circuit with the subscriber's high-voltage cir-

cuit, a low-voltage circuit tapped on the subscriber's high - voltage circuit and a storage battery interposed on the subscriber's high-voltage circuit between the low-voltage circuit and source of power, substantially as specified.

15. An electric system for the transmission of power and for communication, consisting of a main high-voltage circuit, a subscriber's high-voltage circuit tapped on the main high-voltage circuit, a series of lamps or motors in circuit with the subscriber's high-voltage circuit, a low-voltage circuit tapped on the subscriber's high-voltage circuit, telephone instruments in circuit with the subscriber's low-voltage circuit and a storage battery interposed on the subscriber's high-voltage circuit between the low-voltage circuit and main high-voltage circuit, substantially as specified.

20. 16. An electric system for the transmission of power and for communication, consisting of a main high-voltage circuit, a subscriber's high-voltage circuit tapped on the main high-voltage circuit, electric lamps or motors in circuit with the subscriber's high-voltage circuit, a low-voltage circuit tapped on the subscriber's high-voltage circuit, telegraph instruments in circuit with the low-voltage circuit and a storage battery interposed on the subscriber's high-voltage circuit between the low-voltage circuit and the main high-voltage circuit, substantially as specified.

25. 17. An electric system for the transmission of power and for communication, consisting of a main high-voltage circuit, a subscriber's high-voltage circuit tapped on the main high-voltage circuit, a series of lamps or motors in circuit with the subscriber's high-voltage circuit, a low-voltage circuit tapped on the subscriber's high-voltage circuit, a telephone instrument in circuit with the low-voltage circuit, a telegraph instrument in circuit with the telephone-instrument's circuit and a storage battery interposed on the subscriber's high-voltage circuit between the low-voltage circuit and the main high - voltage circuit, substantially as specified.

30. 18. An electric system for the transmission of power and for communication, consisting of a main high-voltage circuit, a subscriber's high-voltage circuit tapped on the main high-voltage circuit, a low-voltage circuit tapped on the subscriber's high-voltage circuit and a secondary circuit adapted to be established 45 through the low-voltage circuit to the main high-voltage circuit, substantially as specified.

35. 19. An electric system for the transmission of power and for communication, consisting of a main high-voltage circuit, a subscriber's high-voltage circuit tapped on the main high-voltage circuit, a low-voltage circuit tapped on the subscriber's high-voltage circuit, a telephone instrument interposed on the low-voltage circuit, a secondary circuit in circuit with 40 the low-voltage circuit and main high-voltage

circuit through the telephone instrument, substantially as specified.

20. An electric system for the transmission of power and for communication, consisting of a main high-voltage circuit, a subscriber's high-voltage circuit tapped on the main high-voltage circuit, a series of lamps or motors in circuit with the subscriber's high-voltage circuit, a low-voltage circuit tapped on the subscriber's high-voltage circuit, a telephone instrument interposed on the low-voltage circuit, a secondary circuit in circuit with the low-voltage circuit, and main high-voltage circuit, and adapted to be established through the telephone instrument, substantially as specified.

25. 21. An electric system for the transmission of power and for communication, consisting of a main high-voltage circuit, a subscriber's high-voltage circuit tapped on the main high-voltage circuit, a series of lamps or motors in circuit with the subscriber's high-voltage circuit, a low-voltage circuit tapped on the subscriber's high-voltage circuit, a telephone instrument interposed on the low-voltage circuit, a secondary circuit in circuit with the low-voltage circuit and main high-voltage circuit through the subscriber's telephone instrument and central station, substantially as specified.

30. 22. An electric system for the transmission of power and for communication, consisting of a high-voltage circuit, a low-voltage circuit tapped on the high-voltage circuit, a storage battery interposed on the high-voltage circuit between the source of power and low-voltage circuit, a subscriber's telephone instrument interposed on the low-voltage circuit, a secondary circuit in circuit with the low-voltage circuit and high-voltage circuit through the subscriber's telephone instrument and central station, a signal-lamp, and a secondary battery adapted to be short-circuited through the signal-lamp by the current flowing through the secondary circuit from the subscriber's telephone instrument to the main high-voltage circuit, substantially as specified.

35. 23. An electric system for the transmission of power and for communication, consisting of a high-voltage circuit, a low-voltage circuit tapped on the high-voltage circuit, a subscriber's telephone instrument interposed on the high-voltage circuit, a central station, a secondary circuit in circuit with the low-voltage circuit and high-voltage circuit through the central station, a storage battery interposed on the high-voltage circuit between the source of power and low-voltage circuit and a signal-lamp operated by the flow of the current through the secondary circuit, substantially as specified.

40. 24. An electric system for the transmission of power and for communication, consisting of a main high-voltage circuit, a subscriber's high-voltage circuit tapped on the main high-

- voltage circuit, a series of lamps or motors in circuit with the subscriber's high-voltage circuit, a low-voltage circuit tapped on the subscriber's high-voltage circuit, a subscriber's telephone instrument interposed on the low-voltage circuit, a storage battery interposed on the subscriber's high-voltage circuit between the main high-voltage circuit and low-voltage circuit, a central station, and a secondary circuit in circuit with the low-voltage circuit and main high-voltage circuit through the subscriber's telephone instrument and central station, substantially as specified.
- 15 25. An electric system for the transmission of power and for communication, consisting of a main high-voltage circuit, a subscriber's high-voltage circuit tapped on the main high-voltage circuit, a series of lamps or motors in circuit with the subscriber's high-voltage circuit, a low-voltage circuit tapped on the subscriber's high-voltage circuit, a subscriber's telephone instrument interposed on the low-voltage circuit, a storage battery interposed on the subscriber's high-voltage circuit between the main high-voltage circuit and low-voltage circuit, a central station, a secondary circuit in circuit with the low-voltage circuit and main high-voltage circuit through the subscriber's telephone instrument and central station, and a telegraph-circuit tapped on the conductor of the secondary circuit, substantially as specified.
- 20 30. An electric system for the transmission of power and for communication, consisting of a main high-voltage circuit, a subscriber's high-voltage circuit tapped on the main high-voltage circuit, a series of lamps or motors in circuit with the subscriber's high-voltage circuit, a low-voltage circuit tapped on the subscriber's high-voltage circuit, a subscriber's telephone instrument interposed on the low-voltage circuit, a storage battery interposed on the subscriber's high-voltage circuit between the main high-voltage circuit and low-voltage circuit, a central station, a secondary circuit in circuit with the low-voltage circuit and main high-voltage circuit through the subscriber's telephone instrument and central station, and a telegraph-circuit tapped on the conductor of the secondary circuit, substantially as specified.
- 25 35. An electric system for the transmission of power and for communication, consisting of a main high-voltage circuit, a subscriber's high-voltage circuit tapped on the main high-voltage circuit, a series of lamps or motors in circuit with the subscriber's high-voltage circuit, a low-voltage circuit tapped on the subscriber's high-voltage circuit, a subscriber's

telephone instrument interposed on the low-voltage circuit, a storage battery interposed on the subscriber's high-voltage circuit between the main high-voltage circuit and low-voltage circuit, a central station, a secondary circuit in circuit with the low-voltage circuit and main high-voltage circuit through the subscriber's telephone instrument and central station, a telegraph-circuit tapped on the conductor of the secondary circuit and a condenser interposed on the conductor of the secondary circuit between the terminals of the telegraph-circuit, substantially as specified.

40 45 50 55 60 65 70 75 27. An electric system for the transmission of power and for communication, consisting of a high-voltage circuit, a low-voltage circuit tapped on the high-voltage circuit, a storage battery interposed on the high-voltage circuit between the source of power and the low-voltage circuit, a series of translating devices, lamps or motors operated by the high-voltage circuit, telephone instruments in circuit with the low-voltage circuit, a secondary circuit in circuit with the low-voltage circuit and main high-voltage circuit through the telephone instrument and central station, and a telegraph-circuit tapped on the conductor of the secondary circuit; substantially as described.

28. An electric system for the transmission of power and for communication, consisting of a high-voltage circuit, a low-voltage circuit tapped on the high-voltage circuit, and a choking means interposed between the source of current and low-voltage circuit, substantially as specified.
